INVENTOR
Amos Newell

United States Patent Office.

AMOS NEWELL, OF REDWING, MINNESOTA, ASSIGNOR TO HIMSELF, HENRY S. BROWN, FREDERICK ARNOLD, AND ALFRED ARNOLD.

Letters Patent No. 81,932, dated September 8, 1868.

IMPROVED ORE AND BONE-CRUSHER.

The Schedule referred to in these Letters Patent and making part of the same.

TO ALL WHOM IT MAY CONCERN:

Be it known that I, AMOS NEWELL, of Redwing, county of Goodhue, and State of Minnesota, have invented an Improvement in "Ore and Bone-Crushers;" and I do hereby declare that the following is a full and exact description thereof, reference being had to the accompanying drawings, and to the letters of reference marked thereon.

My invention relates to that class of ore and bone-crushers wherein the material is crushed by revolving hammers driven with great velocity inside a stationary case.

My invention consists, first, in the employment of two sets of the said revolving hammers, made to revolve in opposite directions, whereby far less velocity is required to produce the same percussion; second, in the general construction and arrangement of the stationary case for its adaptation to the said two sets of hammers, and for the convenient feed and discharge of the mill.

Figure 1 in the drawing is a vertical section through the line *a a* in Figure 2, and shows the plan of the disk *E*, to which the hammers *g* are attached.

Figure 2 is a vertical section through the line *b b* in fig. 1.

A is the stationary case. That portion above the centres of the shafts *D D* is a square box open at the top, and that below the shafts is semicircular. Its periphery, *j*, is perforated, as shown.

Firmly attached to and revolving in opposite directions with the shafts are the disks *E E*, provided with flanges *ffff*, to which the hammers *g g g g* are bolted.

h h are the driving-pulleys; *i i i i*, the boxes or bearings in which the shafts revolve. Two of these bearings are affixed to the case *A*, as shown.

A strong frame, not shown, is so constructed as only to admit the four bearings *i i i i* to rest on it and thus support the entire mill thereon, leaving a sufficient space underneath the case for the free discharge of the crushed material and its accumulation below the mill.

The exact distance that the edges of the hammers on one of the disks should be from those on the other disk must depend on the kind and size of material to be crushed, and the space between the two sets of hammers may be changed, as occasion may require, by changing the widths of the hammers, or otherwise making the said space adjustable.

The size of the perforations in *j* determine the fineness that the material will be crushed.

In the operation of my improved crusher, the ore or bone is thrown into the top of the case *A*, passes down between the disks *E E*, receives the percussion of the hammers *g g g g*, and is crushed thereby, and then discharged through the perforations in *j*.

What I claim as my invention, and desire to secure by Letters Patent, is—

Two distinct sets of hammers, so made and arranged as to revolve in opposite directions, adapted to and in combination with the case *A*, substantially as and for the purpose described.

AMOS NEWELL.

Witnesses:

HENRY STANTON,
ALFRED ARNOLD.
